UNITED STATES PATENT OFFICE.

HARVEY ERTER, OF CECIL, OHIO.

KILN.

1,175,141.

Specification of Letters Patent. Patented Mar. 14, 1916.

Application filed January 6, 1915. Serial No. 849.

To all whom it may concern:

Be it known that I, HARVEY ERTER, a citizen of the United States, residing at Cecil, in the county of Paulding and State 5 of Ohio, have invented certain new and useful Improvements in Kilns, of which the following is a specification, reference being had to the accompanying drawings.

This invention relates to an improved 10 kiln of that type commonly employed for burning drain tile, brick and similar clay products.

It is the primary purpose of my invention to produce a kiln structure embodying 15 an improved arrangement of the heat distributing flues or passages whereby the heat and products of combustion are admitted above, as well as below the kiln floor so that the brick or tile within the furnace will be 20 uniformly burned.

The invention has for an additional object to provide a kiln which may be economically operated, and in which the heat is most effectively utilized so that the time 25 necessary for the proper burning of the clay is reduced to a minimum.

With the above and other objects in view, my invention consists in the novel features of construction, combination, and arrangement of parts to be hereinafter more fully described, claimed, and illustrated in the accompanying drawings, in which,

Figure 1 is a side elevation of a kiln embodying the preferred form of my invention; Fig. 2 is a vertical section; Fig. 3 is a horizontal section taken on the line 3—3 of Fig. 2; and Fig. 4 is a section taken on the line 4—4 of Fig. 3.

Referring in detail to the drawings, 5 40 designates the base or foundation upon which the kiln structure is built. This kiln structure includes the vertical body wall which, in the illustrated form of the invention, is circular and provided with an arched 45 dome 6. Upon the base 5, within the circular body wall of the kiln, a series of parallel vertical walls 7 are built, said walls being spaced from each other and constituting leaders for the products of combustion. 50 Each of these walls is provided with a multiplicity of openings indicated at 8.

Exteriorly of the kiln wall 6, and upon 55 opposite sides thereof, the furnaces, generally indicated by the numeral 9, are built,

four such furnaces being preferably employed in each series, although it is obvious that a greater or less number of such furnaces may be used, in accordance with the desired capacity of the kiln. Each furnace is located directly opposite to an inlet opening 10 in the wall 6 of the kiln and beneath each furnace grate, an ash pit 11 is formed.

Upon the vertical lead walls 7, the floor 60 12 of the kiln is built, said floor consisting of a plurality of rows of fire brick, the bricks in each row being spaced apart and resting at their ends upon the upper edges of the adjacent walls 7. Thus, a plurality of vertical passages is produced between these floor bricks, which communicate with the spaces between the lead walls 7, thus admitting the products of combustion to the interior of the kiln. Upon each side of the 65 kiln and contiguous to the series of furnaces, the fire bricks 12 are arranged compactly or in contact with each other, as this point of entrance from the furnaces into the lead 70 passages beneath the floor, is subjected to a 75 very intense heat.

Vertical flues 13 are built upon the inner face of the kiln wall 5, and communicate at their lower ends with the alternate furnaces 9 of each series. These flues open at 80 their upper ends a considerable distance above the floor 12 and adjacent to the arched dome of the kiln. Four chimneys 14 are also provided, said chimneys being arranged in pairs between the two series of furnaces, and 85 each chimney having two outlet flues with which openings in the kiln wall, indicated at 15, communicate, said openings being located adjacent to the top of the kiln. Each 90 of the chimneys is provided with a suitable damper plate 16 whereby the outlet of the hot air from the interior of the furnace, may 95 be cut off, when desired. The vertical body wall of the kiln is provided with a suitable door, indicated at 17, through which access 100 may be conveniently had to the interior thereof. It is, however, to be understood that, if desired, the inlet opening may be 105 formed in the dome of the kiln.

From the foregoing description, it is believed that the manner of construction, as well as the several advantages of my improved kiln, will be fully and clearly understood. The proper fuel is placed in the several furnaces and successively fired. The 110 heat and products of combustion are admitted from the pair of furnaces in each series

into the lead passages beneath the kiln floor and then pass upwardly against the lower tiers of clay tile or brick arranged upon the kiln floor. The products of combustion from the other furnaces in each series, pass upwardly through the flues 14 and escape from the upper open ends thereof to the interior of the furnace and burn the upper series of brick or tile. Thus, the distribution of the products of combustion from the several furnaces is equalized, and all of the brick within the kiln is subjected to a constant uniform heat. The temperature within the kiln may be readily varied by opening or closing the damper plates 16 in the chimney flues, to a greater or less extent. In this manner, I reduce the consumption of fuel, and thus effect a material economy in the operation of the kiln, and also obtain better results in the burning of the tile or brick, and reduce the time of operation to a minimum. These several advantages obtained from my improved kiln structure, are of primary importance.

While I have shown and described the preferred construction and arrangement of the several features of my improved kiln, it will be understood that the same are susceptible of considerable modification and I, therefore, reserve the privilege of resorting to all such legitimate changes as may be fairly embodied within the spirit and scope of the invention as claimed.

Having thus fully described my invention, what I desire to claim and secure by Letters Patent is:—

In a kiln, a solid base wall, a vertical body

wall built thereon, a solid dome mounted on the body wall, a plurality of spaced vertical walls built upon said base within the kiln and providing upwardly directing heat leads, each of said walls having a plurality of openings therein, said openings being arranged in alinement to provide direct heat passages communicating with the first heat leads, floor tile arranged upon the upper edge of said walls in spaced parallel rows and providing a multiplicity of openings communicating with the upwardly directing heat leads, a series of furnaces on each side of the kiln, said floor adjacent to each series of furnaces being of imperforate construction; certain of the furnaces communicating with the heat leads, interior flues contiguous with the body wall extending upwardly above the floor and communicating at their lower ends with the remaining furnaces, said flues opening into the kiln above the floor thereof and at a point adjacent the top of the body wall, a plurality of chimneys on opposite sides of the body wall of the kiln between the two series of furnaces and communicating with the interior of the kiln above said floor and a damper arranged within each of said chimneys for controlling the outlet of hot air from the interior of the furnace.

In testimony whereof I hereunto affix my signature in the presence of two witnesses.

HARVEY ERTER.
